CLAIM

We claim the ornamental design for a light fixture, as shown and described.

DESCRIPTION

FIG. 1 is a front, top and right side perspective view of the light fixture;

FIG. 2 is a top plan view of the light fixture of FIG. 1;

FIG. 3 is a front view of the light fixture of FIG. 1;

FIG. 4 is a bottom view of the light fixture of FIG. 1;

FIG. 5 is a rear view of the light fixture of FIG. 1;

FIG. 6 is a left side elevational view of the light fixture of FIG. 1;

FIG. 7 is a right side elevational view of the light fixture of FIG. 1;

FIG. 8 is an enlarged front view of the light fixture;

FIG. 9 is an enlarged rear view of the light fixture;

FIG. 10 is an enlarged left side elevational view of the light fixture;

FIG. 11 is an enlarged right side elevational view of the light fixture;

FIG. 12 is an enlarged partial bottom view of the light fixture;

FIG. 13 is an enlarged partial front view of the light fixture;

FIG. 14 is an enlarged partial right side view of the light fixture; and,

FIG. 15 is an enlarged partial left side view of the light fixture.

FIGS. 12-15 include break away lines for ease of illustration.
